JOHN W. NASMITH, OF MANCHESTER, ENGLAND.

COMBING-MACHINE.

1,369,532.

Specification of Letters Patent. Patented Feb. 22, 1921.

Application filed May 27, 1919. Serial No. 300,116.

To all whom it may concern:

Be it known that I, JOHN WILLIAM NASMITH, of Leegate, Mauldeth Road, Heaton Mersey, Manchester, England, have invented certain new and useful Improvements in 5 Combing-Machines, of which the following is a specification.

This invention relates to improvements in 10 combing machines of the Nasmith Heilmann type and will be fully set forth in the following description with reference to the accompanying drawing in which Figures 1, 2, 15 3 and 5 are diagrammatic illustrations, Fig. 4 is a sectional view in elevation, through one head of the machine showing certain parts and Figs. 6 and 6^a are similar views showing other parts. Fig. 6, shows the left 20 hand half of a double machine with the parts in the combing position and Fig. 6^a the right hand side with the parts in the 25 positions occupied during the detaching period and an alternative arrangement of the top comb mechanism.

In the now well-known Nasmith combing 30 machine the nipper swings upon a pivot N placed below the cylinder and the nipper point moves to and fro along an arc AC Fig. 1. During the time that the nipper point traverses the short arc BC and back 35 again the rows of needles mounted upon and occupying about a quarter of the periphery of the cylinder have passed through the tuft of material projecting from and held by the nipper. The short arc BC, for the sake of brevity, may be called the "combing arc" and it is essential that it should be approximately parallel to the periphery of the cylinder. In order to suit different lengths of 40 fibers that compose various materials to be combed, the various growths of cotton for instance, it is necessary to alter the position of the whole arc AC in relation to the detaching roller D, that is to say that for short material the forward extremity A 45 must be considerably nearer to D than for long stapled material and it follows that the combing arc is altered in relation to the periphery of the cylinder. In the original Nasmith comber the theoretical divergence 50 of the combing arc in its various positions in practice, from the periphery of the cylinder, is so small except in extreme cases, as to be negligible, because the cylinder is a circle inside the arc.

55 In the British Letters Patent 3871 of 1914 granted to me the cylinder is a circle ex-

ternal to the arc traversed by the point of the nipper, (Fig. 2). In this case the combing arc coincides sufficiently with the periphery of the cylinder for practical purposes in a given position. But if the whole arc AC Fig. 2 be displaced to the position shown in dotted lines the arc and the curve of the periphery of the cylinder diverge rapidly and combing is affected detrimentally by the nipper being too far from the needles at some part of the combing period.

One object, therefore of the present invention is to provide means whereby the whole arc traversed by the nipper may be altered 70 in relation to the detaching roller D without in any way altering the relation of the combing arc to the cylinder.

To achieve this object one way is to make 75 the pivot on which the nipper oscillates adjustable along an arc having the axis of the combing cylinder as center, or along a line approximating to such arm. It is then clear that by moving the pivot N to *n* Fig. 3, the whole arc AC is moved farther from the 80 detaching roller to the dotted position *ac* without in any way altering the relation of the short combing arc *bc* to the periphery of the cylinder. It is also clear that the farther the point A is withdrawn from the 85 roller D by moving the pivot N toward *n*, the higher the point A is in relation to a horizontal tangent *tT* drawn to touch the top of the roller D, so that during the drawing off or detaching period the material is 90 well supported behind the top comb (T Fig. 6^a), which must always go up to the detaching roller D no matter what may be the position of A. In other words as N is moved toward *n*, the tangent of angle *abt*, that is, 95 the angle between the dotted arc limited by radii *a* and *b*, and the tangent line *tT* is an increasing quantity. When the nipper pivot is at N (Fig. 3) the point A of the arc AC lies on the line *tT* and the angle and its tangent are zero. As N moves to *n* the angle and its tangent rapidly increase as A rises above the line *tT*.

Fig. 4, shows one suitable mechanical arrangement permitting the adjustment of the 105 pivot N. 1. is the cylinder fixed upon the shaft C revolving in bearings 2 the bosses of which project from the framing and upon which levers 3 pivot, one at each side of each head of the machine. Fixed securely in 3 is 110 the nipper pivot N upon which the nipper swings as will be described later. In 3 is

the circular slot 4 and a screw 5 passing through the slot secures the lever 3 in any desired position to the framing 6. The upper end of the lever 3 is connected by the rod 7, provided with adjusting nuts 8 to the lever 9, of which there are two to each head keyed upon the shaft 10 carried in bearings in the frame 6. On the end of the shaft 10 is keyed an index lever 11 provided with a circular slot 12 and secured to the framing 6 by the screw 13. A fixed finger 14 serves as an index to a graduated scale on the edge of the lever 11. The index lever 11 being secured to the framing by tightening the screw 13 the shaft 10 becomes a fixture and the screws 5 being loosened, each of the pivots N throughout the length of the machine may be adjusted separately by the nuts 8 on the rods 7 so as to be all alike in line at any given point on the arc rr which has the axis C of the combing cylinder as center. When this has been done all the pivots N throughout the length of the machine may be adjusted simultaneously to any other desired position by releasing the screw 13 and moving the lever 11 to another point on the scale and securing it there.

Hitherto the adjustment of the distance between the nipper point and the detaching roller D to suit various lengths of fiber was obtained by altering the position of the arc of oscillation of the nipper shaft W by suitable means on the end of it (compare U. S. specification No. 724119). A second object of the present invention is to provide means of making this adjustment independently of the shaft W. The displacement of the nipper pivot N as already described provides this means and alters the distance between the detaching roller D and the point of the nipper when at the forward extremity A of its path (Fig. 3) so that the arc of oscillation of the shaft W may always remain in the same position. Making the nipper pivot adjustable as described therefore achieves three desirable objects:

(1) It keeps the combing arc always in the same relation to the cylinder for all positions of the nipper.

(2) It provides a convenient means of adjusting the distance between the nipper and the detaching roller independently of the nipper shaft and,

(3) When the nipper is set back it raises the point of the nipper and so affords increased support of the material behind the top comb.

The oscillating shaft W from which the nipper receives its to and fro motion is placed above and a little behind the nipper pivot as shown in Figs. 4, 6 and 6^a and is so placed with a three-fold object now to be explained.

Firstly it must be so placed that the lever 65 keyed upon it can be connected to the nip-

per in such a manner that the displacement of the nipper pivot N will not materially affect the amplitude of the arc of oscillation of the nipper but only its position in relation to the detaching roller D. This is diagrammatically illustrated in Fig. 5. If the pivot N be displaced along the arc rr to n the center 16 moves to the dotted position along the arc xx determined by the link 17 swinging on center 20 controlled by the arm 21 on the shaft W and results in displacing the forward end of the path of the nipper from P to p but does not affect the nipper or its movement in any other way.

Secondly it is so placed that the opening and closing of the nipper can be directly obtained from the oscillation of the shaft W and reasoning as above it is obvious that moving N to n Fig. 5 does not disturb either the time or the amount of the opening of the nipper since the pin N4 Figs. 5 and 6 only moves along an arc with N6 as center and,

Thirdly it is so placed that the swinging of the top comb can also be directly controlled from the rocking shaft W (Figs. 6 and 6^a).

In my British Letters Patent 3871/14 the top comb was shown and claimed as pivoted on the same center as the nipper and this might also be done in the present invention. But as the nipper pivot N is now made adjustable the top combs would have to be separately adjusted each time the nipper adjustment was changed as is the case in the original Nasmyth comb. In the above mentioned Letters Patent this was avoided with advantage but it was impracticable to connect the top comb directly to the nipper shaft and a separate operating shaft had to be provided and further as the path of the top comb needles was an arc parallel to that of the nipper point means for lifting the comb at the rear end of its path so as to clear itself every stroke had to be provided also. By placing the nipper shaft as above described in relation to the nipper pivot the top comb can be operated directly from the nipper shaft and the separate shaft and lifting mechanism all dispensed with and the machine greatly simplified. In Figs. 6 and 6^a two methods of operating the comb from the nipper shaft are shown, one shows the right and the other the left side of the machine, the latter being preferred. The comb is also arranged not only to lift off its pivot but to lift bodily off the machine.

The preferred arrangement of Fig. 6 will now be described in detail, along with the general arrangement of the nipper parts. The Fig. 6 is a section through the middle of a head in vertical elevation but omitting the parts shown in Fig. 4 except N, W, and 10.

The arm 15 (one at each side of the head) 130

hinges freely on the adjustable pivot N, the other end carrying a stud 16 on which hinges the link 17 provided with adjusting nuts 18 and passes through a swivel 19 hinging on the stud 20 fixed in one arm of the three-armed lever 21 keyed upon the oscillating shaft W. Secured to the arms 15 at each side of the head is a nipper cheek N2 cast together with the bridge piece B to which is secured the bottom nipper knife P2. Adjustment of this knife to the needles of the cylinder is provided by the screw P the slot S and the screw S1 and the bolt 16 which, when loosened, serves as a pivot for the nipper cheeks N2 during this adjustment. Cast near each end of the bridge piece B are projections to carry the pivots P1 upon which hinge the upper nipper arms N3 carrying the top knife P3. Each arm N3 has cast on it a snug to carry the pin N4 on which the link N5 hinges. The link is arranged in the usual way to easily lift off when it is necessary to raise the top knife for cleaning or other purpose. The link N5 has threaded upon it an open spiral spring abutting against the under face of a swivel N6 pivoting freely in the short arm of the three-armed lever 21. Adjusting nuts N7 are provided above the swivel. When the nipper is closed as shown in Fig. 6, the swivel leaves the nuts and compresses the spring to grip the material between the jaws of the nipper during the combing period. As the shaft W oscillates to its opposite position shown in Fig. 6^a the swivel N6 contacts with the nuts and lifts the top jaw, opening the nipper for detaching, while the spring is dead. Owing to the position of the shaft W this action as already explained, is in no wise affected by the amount of adjustment of the pivot N required in practice.

The top comb blade T is screwed to the bridge T1, secured to the arms T2 provided with circular adjusting slots. T3 is a pivot fixed in the framing of the machine and loosely hung thereon is the piece T4, which is slidably adjustable by means of the set screw T5 on the upper end of the arm T2. Also pivoted on the stud T3 is the independent lever T7, having fixed in its lower end a pin T8 which engages in a groove T10 formed in the arms T2, so that any swinging movement of the pendent levers T7 is imparted to the comb arms. This swinging movement is obtained from a third arm on the lever 21 which is keyed on the shaft W and carries a pin on which the rod T6 pivots. The other end of this rod passes through a swivel T9 and is furnished with adjusting nuts. The piece T9 is accommodated between the arms T2 and the levers T7 and swivels freely on the pin T8. In order to prevent the comb from lifting when working a small latch T11 is freely

pivoted on the lever T7 and drops naturally into a notch formed in the piece T4. When it is desired to lift the comb for any purpose the latch T11 is pushed back out of the notch when the whole comb can be removed bodily from the machine. 70

In this arrangement the arc described by the point of the comb needles is not parallel with that followed by the nipper point but toward the rear end intersects it and rises 75 above it thus obviating the necessity of providing special mechanism for lifting it.

In the arrangement shown in Fig. 6^a, the pivot T3^a on which the top comb rocks is fixed in the top comb arm T2^a and rests in 80 an open bearing formed in the bracket T4^a, which is adjustable in a groove shaped in the stand 6 and provided with adjusting screws T5^a to raise and lower the comb. The upper end of the top comb arm T2^a is 85 connected to the arm 21^a of the lever 21 keyed to the nipper shaft W by means of the rod T6^a. The pivot T3^a is prevented from lifting in the bearing T4^a when at work by some of the usual devices for this 90 purpose.

The mechanism for operating the feed roller is omitted from the drawings, the ordinary arrangement being used.

What I claim and desire to secure by Letters Patent is:—

1. In a combing machine, a combing cylinder, a detaching roller, nippers adjacent to said combing cylinder for holding the fiber to be combed adapted to swing in the 100 arc of a circle adjacent the combing roller, and means whereby the distance between the detaching roller and said arc may be altered without disturbing the relation of the arc to the periphery of the combing cylinder. 105

2. In a combing machine, a combing cylinder, pivotally mounted nippers adapted to swing in the arc of a circle adjacent said cylinder, the pivot point of said nippers being adjustable along an arc of a circle concentric with said cylinder or along a line approximating such an arc. 110

3. In a combing machine, a detaching roller, nippers pivotally mounted to swing 115 in an arc adjacent said detaching roller, a nipper-operating shaft, means for altering the distance between the arc in which said nippers swing and the detaching roller independent of the nipper-operating shaft. 120

4. In a combing machine, a plurality of detaching rollers, a plurality of nippers mounted on pivots to swing in arcs adjacent said detaching rollers, a nipper-operating shaft, and means for simultaneously altering the distance between all of said detaching rollers and the corresponding nippers independent of said operating shaft. 125

5. In a combing machine, a plurality of detaching rollers, a plurality of nippers 130

4

mounted on pivots to swing in arcs adjacent said detaching rollers and means for simultaneously altering the distance between the arcs in which said nippers swing and said 5 detaching rollers.

6. In a combing machine, a plurality of combing cylinders, a plurality of nippers pivotally mounted longitudinal of the machine, the pivots of said nippers being adjustable along arcs of circles concentric with said combing cylinders, said means being of such character that the pivot points of the nippers may be adjusted simultaneously or each adjusted separately.

15 7. In a combing machine, nippers adapted to swing in the arc of a circle and having a pivot point on a lever adapted to be swung on a pivot concentric with the cylinder, and means comprising a second lever and connecting means between said levers, and a shaft extending longitudinally of the machine to which said second lever is key for adjusting the pivot point of said nippers.

8. In a combing machine, a plurality of 25 combing cylinders, a plurality of levers rotatably mounted lengthwise of the machine to move it, so that an arc described by any point thereon will be concentric with the cylinder, nippers pivotally mounted on said 30 levers to swing in an arc adjacent said cylinder, a longitudinally extending shaft in the machine, and a second set of levers extending from said shaft, connecting means between said levers whereby the position of 35 the pivot points of all of the nippers may be adjusted simultaneously, and means comprising nuts screwed onto said connecting means between the levers whereby each of the said pivot points may be adjusted sep- 40 arately.

9. In a combing machine, a combing cyl-

inder, a detaching roller, nippers adjustably pivoted adjacent said combing cylinder and comprising jaws adjustable relative to each other for holding the fiber to be combed, 45 said jaws being adapted to be opened and closed and adapted to swing in an arc of a circle adjacent the said cylinder, and means whereby the distance between the detaching roller and said arc may be altered without 50 disturbing the relation of the arc to the periphery of the combing cylinder, the pivot point of said nippers being adjustable along the arc of a circle concentric with the com- 55 bing cylinder, a nipper-operating shaft located in the machine above and behind the pivot of said nippers, means on said operating shaft whereby the swinging of the nippers and the opening and closing of said jaws may be operated, the adjustment of the 60 pivot point of said jaws being such as not to effect the swinging or the opening and closing thereof.

10. In a combing machine, a detaching roller, a combing cylinder, and a top comb 65 swingingly mounted adjacent thereto and coöoperating therewith, nippers pivotally mounted to swing in an arc adjacent said detaching roller, a nipper operating shaft, means for altering the distance between the 70 arc in which said nippers swing and the detaching roller independently of the nipper-operating shaft, means for connecting the top comb with the nipper-operating shaft in such a manner as to be operated 75 thereby.

In testimony whereof I have affixed my signature in the presence of two witnesses.

J. W. NASMITH.
